UNITED STATES PATENT OFFICE.

FRITZ ALDENDORFF, OF BERLIN-WILMERSDORF, GERMANY; CHARLOTTE ALDENDORFF HEIRESS OF SAID FRITZ ALDENDORFF, DECEASED; SAID FRITZ ALDENDORFF ASSIGNOR OF ONE-FCURTH TO PAUL KOLISCH, OF NEW YORK, N. Y.

AUTOMATIC ELECTRIC SWITCHING SYSTEM.

Original application filed February 14, 1922, Serial No. 536,504, Patent No. 1,641,145, dated September 6, 1927, and in Great Britain August 6, 1921. Divided and this application filed April 7, 1926. Serial No. 100,292.

It is highly desirable to build the switches of electromechanical telephone systems in such a manner that their movable contacts may reach any desired point in a contact bank in the smallest possible time. The speed of travel is, however, limited by the inertia of the relays and magnets by which the movements of the switch wipers are controlled. When a travelling wiper or wipers 10 is to be stopped at a certain contact the relay (or relays) that control the power or actuating circuit has (or have) to be given sufficient time to act and with commercial relays this time generally amounts to between 5 to 10 thousandths of a second. For 15 this reason a wiper through which the energizing current of a test relay or the like flows must remain in touch with the particular bank contact in question for at least the 20 said length of time. In addition to the relays the operating magnet and the circuit elements associated with the relay and magnet have more or less electrical and mechanical inertia so that with practical switches of 25 known types a speed at which the wiper travels over about 25 contacts per second is about the average speed that is compatible with reliable working. These figures are, however, only mentioned to provide a more 30 or less general basis for indicating the object of the invention, but are not intended to limit its scope.

One proposed method of enabling a line 35 finder with a bank of 100 to 500 contact sets to rapidly connect any bank contact set through its wipers to the trunk or link circuit coordinated to the finder consists in dividing the contact bank into a number of groups of bank contact sets and providing 40 the finder with a separate set of wipers for each said group. In the finder of this type one set of wipers is always in the neighbourhood of any particular bank contact set that is to be connected through to the trunk, or 45 in other words, the wipers always have only to travel over a fraction of the distance that has to be covered on a finder equipped with only one set of wipers. Special means are provided in connection with such multiple wiper switches for preventing more 50 than one set of wipers of one and the same

finder from becoming operative simultaneously.

The object of the present invention is to provide a switch or finder whose wipers will rapidly reach any desired set of bank contacts in spite of their having to travel over a considerable distance before the proper set of bank contacts is reached. According to one part of my invention this is accomplished by causing the wipers to travel at a very high speed past all bank contacts that lie in the bank contact groups located between the starting point of the wipers and the bank contact set onto which the wipers 65 are to be set, and by providing group designating contacts in the bank which, even when the wipers travel over them at a very high speed, are of such length, form, or condition that a relay or magnet connected to 70 the hunting wiper will have time enough to act before the wiper leaves the particular group designated contact at which it is to be stopped. When the wipers have reached the proper bank contact group, their speed of 75 travel is diminished to such an extent that the times that a wiper makes contact with each individual contact in the group of bank contact sets that it has reached will be sufficient to enable the relay or magnet by 80 which the individual contact sets are tested, to act in the desired manner.

The means in accordance with the invention by which the aforesaid object can be accomplished are various. The bank of the 85 switch may be divided into major and minor groups and the wipers may accordingly be made to travel at three, instead of only two different speeds. In cases in which it is desirable to have only one type of switch in 90 the entire system, the switches according to the invention may be used as line or trunk finders, group selectors and connectors.

In accordance with the invention a switch having a contact bank with fixed group designating contacts and a wiper adapted to cooperate with the group designating contacts is provided with means by which, after any group designating contact has been electrically marked, a continuously acting driving 100 power is caused to move the wipers of the switch without momentary intermediate

stoppages at a high speed directly to the electrically marked group, whereupon the wiper is moved at a lower speed onto a contact in the particular group of bank contacts that correspond with the said electrically marked group designating contact. The wipers are driven over individual bank contacts at a speed which is too high to enable their stoppage to be effected by an electromagnet or electromagnetic relay controlled by circuits closed through the individual bank contacts, but the group designating bank contacts are long enough to enable a wiper-stopping-magnet to be energized or de-energized by the flow or interruption of current through the long contact and a wiper co-operating with the same. The movable member or rotary member which carries the wipers is moved at a high speed against a movable mechanical stop that marks the particular groups and that is actuated by the current which flows through the group designating contact.

According to a second part of my invention a movable group designating stop is provided for each group and as soon as the high speed movement of the wipers is arrested by the stop the low speed movement of the same is caused to take place. In switches of this kind no group designating bank contacts are needed.

So far as I am aware line finders with high and low speed motion of the wipers for successive group and line selectors are entirely new and I therefore claim such finders broadly.

The wipers of my novel switch may be arranged to always rotate in the same plane and in a preferred form of a switch a shaft 40 with a sleeve displaceable thereon is used.

The wipers of the novel switch may be arranged to always move in the same direction or they may be arranged to move at a high speed until arrested by the mechanical stop 45 and then to rotate slowly in the opposite direction. The wipers may be moved to the desired individual set of bank contacts by imparting rotation to two co-axial members in succession. The one co-axial member in 50 the form of a sleeve may be connected to the shaft by a tensioned spring that turns the sleeve relatively to the shaft when the operation of the switch is initiated.

The switch may be arranged to be operated by only two magnets, one magnet serving to allow the driving force to drive the wipers at a high speed and to arrest them when the designated group is reached, while the second magnet serves to move the wipers 60 at a lower speed until the proper individual bank contact set is reached and to restore the wipers to normal.

In a modified switch three magnets are employed, viz a starting or releasing magnet 65 for releasing the wiper carrier so as to al-

low the continuously acting force or spring to carry the wipers round at a high speed until they reach the designated group, a stopping magnet for stopping the wipers at the said group and a stepping and restoring 70 magnet for first moving the wipers step by step onto the proper individual set of bank contacts and then restoring the wipers or retensioning the spring.

When the switch is used as a numerical switch a separate marking switch is associated with it which is adapted to be set by dialling impulses and to mark the desired bank contact group. This separate marking switch is unnecessary when the novel 80 switch is used as a non-numerical switch such as a line finder.

Other features of the invention will appear hereinafter and in the drawings and claims.

The invention is illustrated in the accompanying drawing in which

Fig. 1 is a diagrammatic side view of the novel switch.

Fig. 2 is a diagrammatic edge view of the 90 same.

Fig. 3 is a perspective of the parts of the switch that operate its off normal contacts.

Fig. 4 shows a cross section through the 95 shaft ratchet and its stepping and holding pawls.

Fig. 5 shows the switch in combination with circuits adapting it to be used as a line finder.

Fig. 6 shows the switch in combination 100 group selector, and

Fig. 7 shows the switch in combination with circuits adapting it to be used as a final selector or connector.

Fig. 8 shows a side view of another modified type of switch.

Fig. 9 is a diagrammatic perspective view, and

Fig. 10 is a diagram of such of the circuits 110 of the switch as are deemed sufficiently elucidative to enable its operation to be understood.

Referring to Figs. 1 and 2 it will be seen that the switch has a shaft 1 on which a 115 ratchet wheel 2 with a sleeve 3 is adapted to rotate. Fixed to the shaft 1 is a disk 4 which carries a pawl 5 adapted to engage with the teeth of the ratchet 2. A spring 6 whose one end is attached to a hub 11 of the disk 4 and whose other end is attached to a projection 7 on the ratchet wheel 2, tends to rotate the ratchet wheel in the direction of the arrow, but in the normal position of the switch a detent 8 combined with the ratchet wheel abuts against a movable stop 9 pivoted on the frame of which a piece 10 is shown in Fig. 2. In juxtaposition to the lower end 5' of the pawl 5 is the armature 12 of a release magnet 13 which, on being 130

energized, swings round the pawl 5 to disengage its top end from the teeth of the ratchet wheel and to swing the hinged stop 9 out of the path of the projection 8. The 5 ratchet wheel with its sleeve 3 and brushes 14, 15, 16, 17 is now quickly rotated by the tensioned spring 6 until the magnet 13 is deenergized and the pawl 5 is jerked by a spring 18 into the path of any one of the 10 teeth of the ratchet wheel. When the pawl 5 engages with one of these teeth a coupling is effected between the ratchet wheel and the disk 4 on shaft 1. The shaft 1 has a ratchet 19 adapted to be rotated step by step by a pawl 20 oscillated by a rotary magnet 21. The brushes 14, 15, 16, 17 rotated with the ratchet wheel 2 wipe over a bank of contacts 15 diagrammatically indicated in Fig. 1. The brush 14 wipes over ten long bank contacts 20 22, 23, 24, 25, 26, 27, 28, 29, 30, 31 each of which occupies an arc of the circle in which ten contacts corresponding to each of the other brushes 15, 16, 17 are arranged. In Fig. 1 for the sake of convenience, only three 25 short contacts 32, 33, 34 are shown to occupy the arc of the long bank contact 26 for example. But in the telephone system described herein there are in reality ten sets of three short bank contacts such as 32, 33, 34 associated with each long bank contact so 30 that whilst the brush 14 wipes over one long contact each of the brushes 15, 16, 17 will wipe over ten corresponding short bank contacts 32, 33, 34 etc. The long contacts together with the brush 14 control the circuit 35 of the magnet 13 and the reason for making the contacts 22, 23 etc. long is to give the magnet 13 and the pawl 5 ample time to effect a coupling between the ratchet wheel 40 2 and the shaft 1 when the brush 14 meets a contact 22, 23 etc. corresponding to the group of contacts in which the trunk or line is located with which a connection is to be established.

45 The ratchet wheel 2 and the disk 4 have short hubs 11' and 11, Figs. 2 and 3. A notch in each of these hubs registers with a notch in the other when the switch is in its normal position and the off normal switch 50 35 will then have its contact springs in their normal position. But as soon as the release magnet 13 is energized and the hub 11' rotates with respect to the hub 11 the springs of the off normal switch are shifted into their off normal positions.

To restore the entire switch into its normal position impulses are sent through the magnet 21, and the pawl 20, whose forward movement is limited by the stop 20' (see 60 Fig. 4), then rotates the ratchet 19 and the disk 4 with the pawl 5. The pawl 5 has a nose 36 at its top end which fits into rounded cavities in the indentations of the ratchet wheel and this nose 36 carries the ratchet wheel round with it until the detent 8 of this 65 wheel strikes against the stop 9. The ratchet wheel will now cease rotating, but the magnet 21 will (by virtue of circuit arrangements hereinafter described) continue rotating the shaft 1 and the disk 4 and the pawl 5 will 70 slip from tooth to tooth of the wheel 2 until it reaches the first tooth 50 and until the notches of the hubs 11' and 11 register with each other and the magnet 21 is deenergized by the action of the off normal switch 35. 75 The spring 6 is fully retensioned during the restoration of the switch by the shaft 1 or hub 11 (to which the end of the spring is attached) being rotated whilst the ratchet wheel 2, to which the other end of the spring 80 6 is attached, is held stationary by the detent 8.

In Figs. 5, 6 and 7 the brushes and magnets of the switches are denoted by the same reference numerals as in Fig. 1 except that indexes are added in Figs. 6 and 7.

In Fig. 5 a substation 100 is shown connected by wires 103, 104 to the bank contacts 105, 106 of the line finder LF and to corresponding bank contacts of other line finders 90 assigned to the same group of subscribers. Associated with each subscriber's line is a line relay, the line relays 101, 101' of two subscribers' lines being shown in the drawing. The wires 107, 108, 109 are private 95 normals leading to the banks of connectors as indicated in Fig. 7.

The other details of the circuits will be readily understood from the following description of the operations which occur 100 in establishing a connection.

It will be assumed that the calling substation 100 desires to establish a connection with the substation No. 123.

When the receiver at the substation 100 is 105 raised the line relay 101 is energized by current flowing from the negative battery pole through the upper winding of the relay 101, back contact 110 of the cut-off relay 102, limb 111 of the calling line, substation 100, 110 limb 112 of the line, back contact 113 of the cut-off relay, lower winding of the line relay to earth. The line relay 101 on energizing renders the calling line busy by opening the contact 114 connected to the private 115 normal 109, distinguishes the substation 100 as a calling station by closing the contact 115 and this connecting the earthed relay 102 to the wire 116, and sends a starting impulse or brush releasing impulse into a 120 line finder LF by closing its contact 117, this impulse flowing from the negative battery pole through 117, 118, normal contact 119, normal contact 14³, brush releasing magnet 13, to earth. The brushes 14, 15, 16, 17 will 125 now immediately fly or rapidly travel round until the brush 14 encounters a long contact which is disconnected from the negative battery pole, such a long contact being in the present instance the contact 120 which is 130

disconnected from the negative battery pole by the contact 121 of the line relay 101 having been opened.

It must be mentioned here that the substation lines multiply connected to the banks of the line finders are ordered in groups of ten each, a negative battery lead 122 being serially connected through contacts 121', 121 etc. of the ten line relays 101', 101 etc. to one of the ten long contacts as 120 of each finder LF belonging to the group of say one hundred subscribers served by the particular group of line finders in question.

The moment the brushes of the finder LF are released the contact spring 123 of the off-normal switch will be raised and will prepare the calling line hunting circuit at the contact 128. But as the line hunting brush 15 travels past its short bank contacts at a high speed the hunting relay will, as yet, not find sufficient time to energize on any calling line. When the group hunting brush 14 encounters the long contact 120 the interval of deenergization of the brush releasing magnet 13 will be long enough to enable it to deenergize and as the movement that the coupling pawl 5, Fig. 1, has to execute in order to couple the brush carrying ratchet to the shaft is very small, the brushes will be coupled to the shaft before they have time to wipe past the entire contact 120. The group hunting brush 14 will travel round on the long contact a certain distance before the operation of coupling the brushes to the shaft is properly effected and to allow for this the long contact 120 may be displaced with respect to its associated groups of ten short contacts (or the brush 14 may be displaced with respect to its three mates 15, 16, 17) to such an extent that at the moment the coupling operation is properly effected and the magnet 13 is properly deenergized the brushes 15, 16, 17 will be positioned at the first set of short bank contacts associated with the long contact 120. The coupling or primary operation of the switch being completed, the secondary operation will now be initiated by the closure of the contact 126 that results from the deenergization of the magnet 13 and completes a circuit for the stepping magnet 21 which may be traced from the negative battery pole, through back contact 127, off-normal contact 128, back contact 126, stepping magnet 21, interrupter 129 to earth. The shaft of the line finder LF with the brushes 14, 15, 16, 17 is now stepped or moved round at such a speed that the line hunting relay 125 has sufficient time to energize when the earthed line-distinguishing contact 116' of the calling line is reached by the line hunting brush 15. The relay 125 is energized by a current flowing from the negative battery pole through 124, (Fig. 6), 125, 15, 116', 115, cut-off relay 102

to earth. The relays 125 and 102 are energized simultaneously, the latter cutting off the line relay 101 at 110 and 113 and establishing a circuit for itself through its own contact 115', and the former opening the circuit of the stepping magnet 21 at 127, 70 maintaining the calling line busy by shunting out a part of the resistance of 125 by means of the contact 128 and connecting the calling line through the contacts 129, 130 to the line relay 131 of the selector, Fig. 6. 75

It will be mentioned here that to prevent the starting of the next line finder in the group to which LF belongs by the call from the substation 100, a relay may be inserted at 132 which momentarily places negative battery on the section 118' of the starting wire at the moment this relay energizes, but which will not send another current impulse through 118', 132, 118' to the next line finder in the group until it is deenergized and then re-energized by another call. Relays of this kind are known.

When the calling line is connected through to the selector, Fig. 6, as described the line relay 131 is energized and closes its contacts 133, 134 while opening its contacts 135, 136. The release relay 137 is immediately energized by current flowing from the negative pole through 133, 137, resistance 138 to earth. If the calling person now abandoned the call the line relay 131 would deenergize and a current impulse would flow from the negative pole through 140, 136, the group selecting magnet 139 to earth. The group selecting magnet would shift the off normal switch 144 out of its normal position, and it would open the contact 124, and close the contact 145. Immediately after the release relay 137 would deenergize on account of its being short circuited by 135. The circuit of the line hunting relay 125 would now be open at 124 (and 143) so that this relay would also be de-energized. The group selecting magnet 139 during its momentary energization closes a contact 146 and energizes the restoring relay 147 of the line finder by a current from the negative pole through 127, 128, left winding of 147, 146 to earth. The restoring relay locks itself by means of a current through its right winding and the contact 148 and impulses now flow from earth through the interrupter 129', magnet 21, contact 149, contact 128, 127, to the negative pole. These impulses continue flowing until the line finder LF is restored to normal by the magnet 21 when the off normal switch 150 will open its contacts 128, 132 and close 119. On the opening of 128 the relay 147 is deenergized and the circuit of the stepping magnet 21 that restores the finder is opened. The line finder will now be ready for a fresh call.

The off normal switch 144 of the selector,

Fig. 6, is restored to normal by impulses flowing from the negative pole, the interrupter 141, 142, 145, magnet 139 to earth, this magnet operating a cam similar to 11, 5 Fig. 5, or any other suitable device which restores the off-normal switch at the proper moment.

The relay 147, after it has once been energized with the aid of the contact 146 is 10 made independent of the group selecting magnet 139 during the restoration of the line finder, by its opening its own contact 157, after its contact 148 has been closed.

It will now be assumed that the calling 15 person does not abandon the call but proceeds with the establishing of the connection by working the dial at the substation and thus causing the interruption of the line relay circuit for the purpose of selecting the 20 desired first hundred groups. The line relay 131 is then deenergized once and a selecting impulse flows through the group selecting magnet 139 from the negative pole through 140, 136, 139 to earth. The group 25 selecting magnet controls the group selecting switch or indicator which consists of a rotatable ring 153, a brush 152 applying negative battery to the ring, and contacts 154 against which the ring 153 slides. Normally the ring applies negative battery to 30 all the contacts 154, but it has a gap at one part of its circumference as shown and this gap may be made to register with any of the contacts 154 by the ring being rotated by 35 the magnet 139. The particular contact 154 with which the gap in the ring is made to register will correspond to the group to be selected by the selector. The contacts 154 are each connected to a long contact, as 22', the 40 function of these long contacts being similar to those of the line finder, i. e. to designate the group of bank contacts at which the brushes 14', 15', 16', 17' shall be coupled with the shaft of the selector.

It must now be explained that during oscillations of the armature of the line relay 45 the change-over relay 155 is maintained energized by current flowing from the negative pole through 140, 155, resistance 156 to earth, but that when the said oscillations cease the change-over relay 155 is short circuited by 134 so that it lets its armature drop back to close the circuit of the brush releasing magnet 13', this circuit extending 50 from earth through 13', 14', 165, 166, 157, 140, to the negative pole.

Since the gap in the ring 153 has been set opposite to the first group distinguishing contact 154 the magnet 13', which would 60 otherwise be energized by a current from earth through 13', 14', 22', 154, ring 153, wiper 152 to the negative pole, is deenergized when the brush wipes over the first long contact 22' and hence the brushes are coupled to 65 the shaft of the selector and are then ad-

vanced step by step by current impulses flowing from the negative pole through the interrupter 158, contact 159 of the test-relay 160, contact 161 of the off-normal switch 164 of the selector, contact 163 of the now de-energized brush releasing magnet 13', stepping magnet 21' to earth. The stepping magnet 21' now steps the shaft and brushes 14', 15', 16', 17' round at a slow rate in search of a free trunk. Assuming that the trunk 200, 70 201, 203 is free, the test relay 160 will be energized when the test brush 15' encounters the bank contact connected to the test wire 203. The current for the test relay 160 flows from the negative pole through 160, brush 80 15', test wire 203, resistance 204, contact 205 of off-normal switch 206, to earth. The test relay 160 now connects the trunk 180, 181 through contacts 182, 183 to the trunk 200, 201 and to the line relay 207 of the 85 connector, Fig. 7. At the same time the test relay 160 disconnects (at contacts 184, 185) the line relay 131 of the selector from the trunk 180, but maintains this relay 131 energized by means of the contact 186. 90

The line relay 207 will now be energized by current flowing through the trunks 200, 201 and 180, 181, and the line 111, 112. The release relay 208 is energized by current flowing from the negative battery pole 95 through 209, 208, resistance 210 to earth. The release relay locks itself through its armature 211 and closes the contacts 212, 213, whilst opening the contacts 214, 215. The change-over relay 216 is short-circuited 100 at 217.

If the calling person now abandons the call the line relay 207 will be deenergized and after a short interval the release relay 208 will also be deenergized in a similar manner 105 to that explained in connection with the operation of the selector. A current impulse will be sent from the negative pole through 211, 219, 220 and through the tens selecting magnet 222 to earth, whereby the off-normal 110 switch will be shifted and the contact 205 opened. Immediately after the contact 213 will also be opened and hence the test relay 160 in the selector, Fig. 6, will be deenergized. The off-normal switch 206 will be 115 restored to normal by impulses flowing from the negative pole through the interrupter 220', contact 214, contact 221, tens magnet 222 to earth.

As a result of the deenergization of 131 120 the selector will be restored to normal by impulses flowing from the negative pole through the interrupter 141, 142, 162, stepping magnet 21' to earth, and by other impulses flowing from the negative pole 125 through 141, 145, magnet 139 to earth.

It will now be supposed that the calling person does not abandon the call but works his dial in accordance with the tens digit 130 which is 2. The line relay 207 will then

be deenergized twice and two impulses will flow from the negative pole through 211, 219, 220, tens selecting magnet 222 to earth. The tens selecting magnet sets the gap in 5 the ring 223 opposite the second tens contact so that the second long contact 224 is disconnected from the battery. During the flow of the tens dialling impulses the change-over relay 216 is energized by current flowing from the negative pole through 10 211, 216 resistance 225 to earth. But when the tens dialling impulses cease the change over relay is deenergized by its being continuously short-circuited at 217 so that the 15 contact 218 is closed and a brush releasing impulse is sent from the negative pole through 211, 218, 227, 14², brush releasing magnet 13² to earth. The brushes 14², 15² 20 16² will now fly round until the brush 14² encounters the long contact 224 which is disconnected from battery when the said brushes will be coupled to the connector shaft in the same way as in the case of the line finder and selector. When the brushes 25 fly round as described the off-normal switch 228 opens its contact 220 and closes its contacts 229, 230'. On the calling person now sending in the last series of dialling impulses, units impulses will now flow from 30 the negative pole through 211, 219, 236, wire 231, 212, 229, stepping magnet 21² to earth. The brushes 15², 16², 17² are thus stepped round to the third set of bank contacts in the second group of ten sets. The said units 35 impulses also flow through a branch path in which they energize the relay 230 and prepare a test circuit at 232. When the units dialling impulses cease the change-over relay is again deenergized and a test impulse 40 then flows from the negative pole through 211, 218, 232, test relay 233, test brush 15², test wire 109¹ and then through a contact (corresponding to 114) on the line relay of the wanted line and through the cut-off relay (corresponding to 102) of the wanted 45 line. Of course, if the wanted line is calling its line relay will be energized and its guarding contact will be open to prevent its being connected to by any connector. In such a case 50 the test relay 233 will not be energized and a busy tone will be placed on the calling line, this tone emanating from the busy tone producer 239 and passing through 240, 235¹ to the talking circuit 201 and to the calling station. The calling person will then replace 55 his receiver and the line relays 207, 131 will deenergize and give rise to the restoration of the switches in the manner already described.

60 If the wanted line is free at the moment when the test brush 15² is set onto the test wire 109¹ the relay 233 will be energized by a current flowing from the negative pole through 211, 218, 232, 233, 15², 109¹, contact 65 (similar to 114) on the line relay of the

wanted subscriber's line, cut-off relay of the wanted subscriber to earth. The test relay 233 renders the wanted line busy by short-circuiting of part of its own winding at 234, disconnects the busy tone producer at 235¹, 70 connects the ringing current generator 245 through the contacts 236, 237 to the wanted line, and closes the circuit of the interrupter relay 246 at 238, this circuit extending from the negative pole through the ringing interrupter 247, 238, contact 248 of the auxiliary release relay 249, 246, to earth. The ringing current generator 245 is intermittently disconnected from and the relay 250 intermittently connected to, the wanted line by 80 the relay 246. When the wanted party responds transmitter feed current flows out over his line through the relay 250 which energizes and opens its contact 251 while closing its contact 252 and thus energizing 85 the auxiliary release relay 249 by a current flowing from earth through 252, right winding of 249 to the negative pole. The relay 249 locks itself energized by a current flowing from the negative pole through 211, 253, 90 left winding of 249, to earth.

If the calling person hangs up his receiver first at the end of the conversation the restoration of the switches takes place in the manner already described. If the wanted 95 party hangs up his receiver first the deenergization of the relay 250 results in the release relay 208 being short circuited through the closed contacts 254 and 251. Hence the release relay 208 will deenergize and cause 100 the restoration of the connector. The selector and line finder will also be restored when the calling party hangs up.

The scope of the invention is not limited to any particular type of switch or circuits. 105 The fundamental feature underlying the invention is that the contact group of the switch into which the brushes or wipers are to be moved is predetermined by a contact-group-indicating means, whereupon the 110 wipers are moved in a single continuous step and at a relatively high speed into the indicated group, and subsequently at a lower speed onto the desired line or trunk in the said group.

A modified type of switch in which three magnets are employed is shown in Figs. 8 to 115 10.

In Fig. 8 500 is a fixed or stationary shaft on which is revolvably mounted a wheel 501 with coarse and fine teeth 502 and 503 respectively. Protruding from the wheel 501 is a sleeve 504 which carries brushes or wipers 506, 507, 508, 509 brush 506 being adapted to wipe over ten long contacts 506', 506², 506³ etc. Each of the other three rows of bank contacts has ten contacts such as 509', 509² . . . 509⁶ for each of the long contacts 506', 506², etc. A tensioned spiral spring 510 whose ends are attached to the fixed 120

shaft 500 and to the wheel 501 respectively tends to whirl round the wheel 501 with its brushes 506, 507, 508, 509 in the direction of the arrow but is normally prevented from 5 doing so by a detent 511 controlled by a magnet 512. In addition to the magnet 512 the switch has a stepping magnet 513 and a stopping magnet 514 which moves a stop 10 into the path of one of the long teeth 502 when the brush 506 encounters a long contact 506', 506² . . . that is connected to battery or that has had a potential applied to it which denotes that the brushes are to be stopped at that particular designating 15 contact 506', 506² . . . The switch may also be provided with an off-normal switch consisting of the springs 516, 517, 518 and a change-over switch comprising the springs 519, 520, 521. 20 The operation of the switch will now be more fully described with reference to the circuit diagram Fig. 10. 25 It will be supposed that the switch is to act as a line finder and that a subscriber calls whose line is connected to a set of bank contacts in the group of bank contacts that corresponds to the group designating contact 506³. A starting current impulse will be sent by means of the subscriber's line relay 30 (similarly as described in connection with Fig. 5) through the starting wire 523, off-normal switch springs 517, 518, magnet 512 to earth. The magnet 512 is thus energized and pulls the detent out of engagement with the fine teeth 503. The tensioned spring 510 then whirls the wheel 501 with the brushes 506, 507, 508, 509 round until the brush 506 encounters the long contact 506³ that is connected to battery, when the magnet 514 will be energized so as to raise the stop 515 and to bring it into the path of the third tooth 502. The third tooth 502 will strike against the end of the stop 515 and swing the member 525 round on its pivot 526 so as to separate the contact springs 519, 520 and to close the contact 520, 521. The opening of the contact 519, 520 results in the deenergization of the detent magnet 512 so that the detent 511 will engage with a fine tooth 503. The closure of the contact 520, 521 results in the energization of a relay 522 which attracts its armatures 526, 527. At its contact 526 the relay 522 locks itself energized and at its contact 527 the relay 522 closes a stepping circuit which includes the interrupter 528 and the stepping magnet 513. The stepping magnet therefore receives current impulses which will continue flowing until the wipers 506, 507, 508, 509 are 55 stepped back, i. e. are stepped round in the opposite direction to that indicated by arrow, onto the set of bank contacts to which the calling line is connected. The moment the wipers reach the set of contacts the circuit of the 60 magnet 513 will be opened (say at 529) by a line hunting relay in the manner described with reference to Fig. 5. The restoration of the switch to normal is accomplished by stepping round the wheel 501 with the aid of the magnet 513 until the off-normal switch 518 drops down into the notch in the sleeve 504 as shown in Fig. 8. The wipers of the switch will then have regained their normal position and the spring 510 will then also be fully retensioned. 65 The brush carrier 501 could, in certain cases, be arranged in such a way that while the brushes are being whirled round to the desired group of contacts only the group hunting brush 506 wipes over its contacts 70 while the other brushes only commence contacting with their bank contacts after they have reached the desired contact group. Furthermore, the lengths of the group designating contacts 506', 506² etc. and the 75 teeth 502 could be made different so as to allow for difference in the speed at which the brushes are whirled past different parts of the contact bank. To increase the probability of the armature of the stopping magnet 90 514 being attracted soon enough to throw the stopping pawl into the path of the proper tooth 502, the group designating contacts 506', 506² etc. may be displaced with respect to their groups of short contacts in 95 such a way that the group hunting brush 506 reaches the particular group designating contact (506', 506² etc.) before the free end of the stopping pawl 515 is opposite to the gap, say 502', next to the tooth, say 502², 100 that is to strike against the stopping pawl 515. 105 When the switches of the novel type described herein are used as line finders the section of the contact bank or the contact group to which the brushes fly under the influence of a spring, or to which they are moved at a high speed by a rotating shaft or the like, need not be very accurately indicated. In the case of the switch shown in Fig. 8 for example the long contact of the 110 particular contact group to which the brushes are to be moved and all the other long contacts beyond said long contact may be brought to the electrical condition that results in the initial motion of the brushes being stopped. Thus if the brushes are to be set onto a contact in, say, the fourth group, not only the fourth group-indicating or long contact but also a number or all of the long contacts (the fifth, sixth, etc. long contacts) 115 beyond it could be brought into an electrical condition that would result in the deenergization of the release magnet, so that if the stopping pawl fails to act while the brushes are traversing the said fourth contact-group, it would act while the brushes are wiping past the fifth group. After the stopping 120 125

pawl has acted the brushes would then be moved at a lower speed over contacts of the fifth contact-group and then over contacts in the fourth group until the proper contact set is ultimately reached.

I claim:

1. In a switch, a contact bank having fixed individual contacts divided into groups and group designating contacts, a wiper adapted to cooperate with said group designating contacts, a power means for driving said wiper without intermediate stoppages up to any designated group, a toothed member that travels with said wiper, a stopping member that engages said toothed member to stop the brush when it reaches the designated group, an electromagnet for operating said stopping member, and means for moving the brush to an individual contact in the designated group after it has been stopped by the engagement of said stopping member by said toothed member.
2. In a switch, a contact bank having fixed individual contacts divided into groups and group designating contacts, a wiper adapted to cooperate with said group designating contacts, a spring for driving said wiper without intermediate stoppages up to any designated group, a toothed member that travels with said wiper, a stopping member that engages said toothed member to stop the brush when it reaches the designated group, an electromagnet for operating said stopping member, and means for moving the brush to an individual contact in the designated group after it has been stopped by the engagement of said stopping member by said toothed member.
3. In a switch, a contact bank comprising groups of individual contacts and a group designating contact of the length of a plurality of individual contacts, wipers adapted to travel over said contacts, means controlled by a calling station for electrically marking any said group designating contact, and a wiper stopping magnet for arresting the wipers when they reach the electrically marked group of bank contacts.
4. In a high speed and low speed switch, a contact bank comprising groups of individual contacts and a group designating contact for each group adapted to be electrically marked under control of a calling station, wipers that travel over said contacts, a wiper stopping magnet, an electric circuit that extends through said magnet and said designating contacts, a wiper stopping means operated by said magnet to stop the high speed motion of the wipers in response to a change of current in said electric circuit during the travel of the wipers, and means for subsequently operating the wipers at a lower speed of travel.
5. In a multi-position switch, bank contacts divided into groups adapted to be elec-

trically marked under control of a calling station, wipers that travel over said bank contacts, a positively acting member that positively stops the wipers at the proper contact group, and a magnet for operating said member that is energized by a current that flows through a said wiper and a bank contact that is approximately as long as a plurality of individual bank contacts of a said contact group.

6. In a switch, a contact bank having fixed individual contacts divided into groups and group designating contacts, a rotating wiper adapted to cooperate with said group designating contacts, a power means for driving said wiper without intermediate stoppages up to any designated group, a toothed member that travels with said wiper, a stopping member that engages said toothed member to stop the brush when it reaches the designated group, an electromagnet for operating said stopping member, and means for moving the brush to an individual contact in the designated group after it has been stopped by the engagement of said stopping member by said toothed member.

7. In a switch, a contact bank having fixed individual contacts divided into groups and group designating contacts, a rotating wiper adapted to cooperate with said group designating contacts, a spring for driving said wiper without intermediate stoppages up to any designated group, a toothed member that travels with said wiper, a stopping member that engages said toothed member to stop the brush when it reaches the designated group, an electromagnet for operating said stopping member, and means for moving the brush to an individual contact in the designated group after it has been stopped by the engagement of said stopping member by said toothed member.

8. In a switch, a contact bank comprising groups of individual contacts and a group designating contact of the length of a plurality of individual contacts for each group, rotating wipers adapted to travel over said contacts, means controlled by a calling subscriber for electrically marking any said group designating contact, and a wiper stopping magnet for arresting the wipers when they reach the electrically marked group of bank contacts.

9. In a high speed and low speed switch, a contact bank comprising groups of individual contacts and a group designating contact for each group, rotating wipers that travel over said contacts, a wiper stopping magnet, an electric circuit that extends through said magnet and said designating contacts, a wiper stopping means operated by said magnet to stop the high speed motion of the wipers in response to a change

- of current in said electric circuit during the travel of wipers, and means for subsequently operating the wipers at a lower speed of travel.
- 5 10. In a multi-position switch, bank contacts divided into groups adapted to be electrically marked under control of a calling station, rotating wipers that travel over said bank contacts, a positively acting member 70
- 10 that positively stops the wipers at the proper contact group, and a magnet for operating said member that is energized by a current that flows through a said wiper and a bank contact that is approximately as long 75
- 15 as a plurality of individual bank contacts of a said contact group.
11. A switch comprising bank contact groups, calling telephone lines connected to said contacts, wipers, means for moving said 80
- 20 wipers over a plurality of said bank contact groups at a high speed, a positively acting stopping device for stopping the wipers at the desired bank contact group, and means for subsequently operating the 85
- 25 wipers at a lower speed of travel.
12. A switch with bank contacts arranged in groups, calling telephone lines connected to said contacts, means controlled by a calling line for designating a particular group 90
- 30 of contacts, wipers that travel over said contacts, means for driving the wipers in continuous motion to the neighbourhood of an individual contact, and means for subsequently driving the wipers more slowly to 95
- 35 said individual contact.
13. A switch with bank contacts, wipers, calling telephone lines, relays associated with said lines for applying marking potential to individual bank contacts and 100
- 40 group designating contacts, means for driving said wipers at a high speed to a position marked by a group designating contact and subsequently at a lower speed to a position marked by an individual bank contact. 105
- 45 14. A switch with bank contacts, wipers, calling telephone lines, relays associated with said lines for applying marking potential to individual bank contacts and group designating contacts, means for driving said wipers at a high speed to a position marked by a group designating contact and subsequently step by step at a lower speed to a position marked by an individual bank contact. 110
- 50 15. In a hunting switch, individual bank contacts divided into groups, group designating bank contacts of the length of a plurality of individual contacts adapted to be electrically marked under control of a calling station, wipers driven by a continuously 115
- 55 acting force at a high speed to a bank contact group electrically marked by a said group designating contact, and means for driving the wipers at a lower speed after they have stopped at the designated group.
- 60 16. In a switch, bank contacts divided into groups, group designating contacts of the length of a plurality of bank contacts and adapted to be selectively marked under the control of a calling subscriber, wipers, means for driving said wipers in a continuous motion at a high speed over said contacts, group testing means for rendering said driving means inoperative when the wipers reach a designated group, and testing means 70
- 65 for testing lines individually to stop the wipers on an individual set of bank contacts. 75
17. In a switch, bank contacts, calling telephone lines connected to said contacts, rotary wipers adapted to travel over said contacts, spring motor means for driving the wipers in continuous motion to the neighbourhood of an individual contact, and step-by-step means for subsequently driving the wipers step by step to said individual contact. 80
- 85 18. In combination with a switch, bank contacts, rotary wipers, calling telephone lines, relays associated with said lines for applying marking potential to individual bank contacts and group designating contacts, power storing means for driving said wipers at a high speed to a position marked by a group designating contact and means subsequently effective to drive said wipers step by step at a lower speed to a position marked by an individual bank contact. 90
- 95 19. In a hunting switch, individual bank contacts divided into groups, group designating bank contacts adapted to be electrically marked by a calling station, rotary wipers driven by a power storing means at a high speed to a bank contact group electrically marked by a said group designating contact, and means for driving the wipers at a lower speed after they have stopped at the 100
- 100 designated group.
20. In a switch, bank contacts divided into groups adapted to be electrically marked by a calling station, rotary wipers, a spring motor for driving said wipers in a continuous motion at a high speed over said contacts, group testing means for rendering said driving means inoperative when the wipers reach a designated group, and testing means for testing lines individually to stop the 105
- 105 wipers on an individual set of bank contacts.
21. A line finder comprising bank contacts, wipers, a spring for driving the wipers, and an electromagnetically controlled armature for positively stopping the 110
- 115 wipers at a desired position in the contact bank.
22. A line finder comprising bank contacts, rotary wipers, a spring for driving the wipers, and an electromagnetically controlled armature for positively stopping the 120
- 125 wipers at a desired position in the contact bank.
23. A switch comprising bank contacts divided into groups each group adapted to 130
- 135

be electrically marked under control of a calling station, wipers, power storing means for driving said wipers in a continuous motion at a high speed over said contacts, 5 wiper controlling means for rendering said driving means inoperative when the wipers reach a desired bank contact group, and testing means for testing bank contacts individually after the wipers have reached the desired group.

24. In a telephone system, non-numerical switches, numerical switches, all of said switches adapted to execute separate group and individual line selecting movements, 15 means controlled by a calling subscriber for marking a desired group and a desired line in the desired group at certain of said switches, power storing means for each switch for effecting the group movements 20 thereof and separate intermittent power mechanism for each switch for executing the line selecting movements thereof.

25. In a telephone system, calling lines, numerical switches adapted to execute separate group and line selecting movements, spring motive means adapted to execute the group selective movements of the switches, automatic impulsing mechanism for executing the line selecting movements of the 30 switches, and wiper controlling means operated by currents that flow over the two wires of a calling line in series.

26. In a telephone system, calling lines, wanted lines, and numerical selectors for 35 selecting wanted lines, said selectors comprising bank contacts divided onto groups and connected to said wanted lines, wipers, a continuously operative power means for driving said wipers into a desired bank contact group, wiper controlling means operated from a said calling line by electric currents flowing over two wires of the line in series and adapted to determine the amount of travel imparted to the wipers by said 40 continuously operative power means, and means for moving the wipers step by step with the aid of said wiper controlling means after the wipers have been driven onto a desired group.

50 27. In a telephone system, trunks, group selectors provided with wipers for selecting groups of wanted trunks and a free trunk in a group, a continuously operative power means for driving said wipers onto a desired group of trunks, wiper controlling means 55 operated from a said calling line by electric currents flowing over two wires of the calling line in series and adapted to determine the amount of travel imparted to the wipers by said continuously operative power means, and means for subsequently moving the wipers step by step until they reach a free trunk.

60 28. In a telephone system, calling lines, wanted lines, and numerical selectors for

selecting wanted lines, said selectors comprising bank contacts divided into groups and connected to said wanted lines, wipers, a spring for driving said wipers onto a desired bank contact group, wiper controlling means 70 operated from a said calling line by electric currents flowing over two wires of the line in series and adapted to determine the amount of travel imparted to the wipers by said spring, and means for moving the 75 wipers step by step with the aid of said wiper controlling means after the wipers have been driven onto a desired group.

29. In a telephone system, trunks, group selectors comprising wipers for selecting groups of wanted trunks and a free trunk in a group, a spring for driving said wipers onto a desired group of trunks, wiper controlling means operated from a said calling line by electric currents flowing over two 85 wires of the calling line in series and adapted to determine the amount of travel imparted to the wipers by said spring, and means for subsequently moving the wipers step by step until they have reached a free 90 trunk.

30. In a switch, a sleeve and shaft interconnected by a spring that turns the sleeve relatively to the shaft where the operation of the switch is initiated, bank contacts 95 divided into groups, wipers that travel over said contacts, a magnet for releasing the sleeve so that the spring may rotate it until a group hunting wiper reaches a said group, and another magnet that moves the wipers 100 step by step until the proper individual bank contact is reached.

31. In a switch, bank contacts divided into groups, wipers that travel over said bank contacts, a spring for driving said wipers, 105 means for retensioning said spring after each use of the switch, a magnet for stopping the spring driven wipers at the proper bank contact group, and a stepping magnet for stepping the wipers onto the proper individual bank contact in the group.

32. In a switch, bank contacts divided into groups, group designating bank contacts, spring driven wipers that travel over said contacts, a numerical group designating 115 switch for marking the proper group designating bank contact, and means for subsequently causing the wipers to hunt for a free trunk connected to a said group of bank contacts.

33. In a rotary one-motion switch, bank contacts divided into groups, wipers that travel over said bank contacts, a spring for driving said wipers, means for retensioning said spring after each use of the switch, a 125 magnet for stopping the spring driven wipers at the proper bank contact group, and a stepping magnet for stepping the wipers onto the proper individual bank contact in the group.

34. In a rotary one-motion switch, bank contacts divided into groups, group designating bank contacts, spring driven wipers that travel over said contacts, a numerical group designating switch for marking the proper group designating bank contact, and means for subsequently causing the wipers to hunt for a free trunk connected to a said group of bank contacts.
- 10 35. In a telephone system, non-numerical switches, numerical switches, the numerical switches adapted to execute under control of a calling station separate group and line selecting movements, spring power means
- 15 for effecting the group selective movement of each of said switches, and means for storing power in the spring upon the restoration of the associated switch.
- 20 36. In a telephone system, non-numerical switches, numerical switches, each of said switches having circuit closing wipers and co-operating bank contacts and means for moving the wipers of any switch onto the desired set of bank contacts by imparting
- 25 rotation to two coaxial members in succession.
37. In a line finder, a single arcuate level of bank contact sets, wipers, means for driving the wipers over said bank contact sets first in a continuous high speed motion and then at a lower speed in a step-by-step movement.
38. In a telephone system, calling and called lines, calling line finders and numerical switches adapted to execute group and line selecting movements under control of numerical impulses for connecting any calling line to any called line, and spring driven wipers in all said finders and switches.
39. In a telephone system, calling and called lines, switches adapted to execute group and line selecting movements under control of numerical impulses for interconnecting any two of said lines, wipers, springs in all said switches for moving said wipers, and means for automatically retensioning any said spring after use.

In testimony whereof I have affixed my signature.

FRITZ ALDENDORFF.
